US0D1094493S

(12) **United States Design Patent** (10) **Patent No.:** **US D1,094,493 S**
(45) **Date of Patent:** **** Sep. 23, 2025**

(54) **MILLING TOOL**

(71) Applicant: **Betek GmbH & Co. KG**, Aichhalden (DE)

(72) Inventor: **Sebastian Bugdol**, Lauterbach (DE)

(73) Assignee: **Betek GmbH & Co. KG** (DE)

(**) Term: **15 Years**

(21) Appl. No.: **35/521,173**

(22) Filed: **Feb. 8, 2024**

(80) **Hague Agreement Data**

Int. Filing Date: **Feb. 8, 2024**

Int. Reg. No.: **DM/237268**

Int. Reg. Date: **Feb. 8, 2024**

Int. Reg. Pub. Date: **Jun. 7, 2024**

(51) **LOC (15) Cl.** **08-01**

(52) **U.S. Cl.**

USPC **D15/139**

(58) **Field of Classification Search**

USPC D15/29, 127, 131, 138-139; D8/20, 70, D8/86, 98

CPC .. B23C 5/02; B23C 5/12; B23C 5/202; B23Q 27/00; E21C 35/18

(57)

CLAIM

The ornamental design for a milling tool as shown and described.

DESCRIPTION

3. Milling tool

3.1: Perspective

3.2: Front

3.3: Back

3.4: Left

3.5: Right

3.6: Bottom

3.7: Top

The portions of the article shown in broken lines in Figure 3.6 form no part of the claimed design.

1 Claim, 7 Drawing Sheets
